EXHAUST MACHINE

George E. Ott, Eastlake, and Donald B. Torr, Cleveland, Ohio, assignors to General Electric Company, a corporation of New York

Application March 15, 1957, Serial No. 646,376

8 Claims. (Cl. 137—634)

Our invention relates, in one of its aspects, to an exhaust and gas filling machine and, in another of its aspects, to a novel camming mechanism especially useful in such a machine but also having a more general application.

It is an object of our invention to provide a machine for exhausting and/or gas filling a container or envelope, such as an electric lamp bulb, wherein the valves are operated by a novel cam arrangement in a predetermined cyclic pattern and providing for improved control of the operation. It is a further object to provide a novel cam arrangement wherein certain camming functions are divided between separate cams on separate shafts revolving at different predetermined speeds and which make it possible to perform certain cyclic operations which, if derived from a single cam, would provide insufficient camming surface for accurate control or, alternatively, would require a cam of inordinately large size.

Further features and advantages of our invention will appear from the following description of a species thereof and from the drawings wherein:

Fig. 1 is a front elevation of a semi-automatic machine for exhausting and gas filling electric incandescent lamps and which embodies our invention;

Fig. 2 is a fragmentary elevation, in section, of means for connecting the lamp with an electrical current supply;

Fig. 3 is a fragmentary elevation, in section, of a valve assembly and an exhaust port supported thereby;

Fig. 4 is a plan view of the valve assembly and exhaust port; and

Fig. 5 is a perspective view of the valve-operating cam assembly.

Referring to Fig. 1, the lamp 1 to be exhausted is of the well-known high-wattage "bipost" type comprising a glass bulb 2 having a glass neck or base portion with a pair of metal terminal prongs or posts 3 projecting therefrom and a glass exhaust tube 4 also extending therefrom between the posts 3 and communicating with the interior of the bulb. The posts 3 support a filament structure (not shown) within the bulb 2. The lamp is placed base down on a platform 5 with the posts 3 and exhaust tube 4 extending through openings therein. The platform 5 (Fig. 2) is composed of a sheet 6 of stainless steel, a sheet 7 of asbestos and a plate 8 of ordinary steel. The lamp is also supported by pairs of asbestos buttons 9 on three T-shaped supports 10 mounted on the platform 5. The platform is resiliently supported from a table 11 by legs composed of spring-loaded telescoping pairs of hollow columns 12 and 13.

The exhaust tube 4 of the lamp fits into a manually operated compression chuck or exhaust port 14 (Fig. 3) of a conventional type wherein the tube 4 is clamped by a rubber ring 15 which is compressed by rotation of a nut 16 by means of a handle or arm 17 attached thereto.

The chuck 14 is mounted on an assembly 18 of three mechanically operated poppet valves (Figs. 3 and 4), one (19) for rough or preliminary vacuum, one (20) for fine vacuum and the other (21) for nitrogen gas. The ex-

2

haust valves 19 and 20 are similar in construction, and the stems of each of the three valves are sealed by diaphragms 18'.

During the exhaust process, the lamp 1 is preferably baked by heat derived from lighting of its filament. Electrical connection is made to the lamp, through its terminal posts 3, by means of a pair of contact blocks 22 (Fig. 2) fitted with spring clips 23. The blocks 22 are carried by an insulating plate or disc 24 which slides on studs 25 attached to the plate 8 and which is provided with an aperture 26 for passage of the exhaust tube 4 therethrough. The contacts blocks 22 are raised into engagement with the lamp posts 3 by a downward thrust on a lever 27 which is pivoted at 28 (Fig. 1) and has a yoke-shaped end, each arm of which is connected by a pin 29 to a link 30 which is connected by a pin 31 at its other end to a bracket 32 fixed to the plate member 24.

During the exhausting operation, the lamp 1 is enclosed in a cylindrical shield 33 which is suspended from its closed top by a chain 34 which runs over suitable pulleys or sprockets, one of which is shown at 35 in Fig. 1. The other end of the chain is attached to a suitable counterweight 36, and the shield 33 is preferably arranged to be guided by engagement of rollers thereon (not shown) with a pair of vertical rails 37 from which the pulleys 35 are supported by the cross member 38 and bracket 39. The shield 33 comprises three concentric cylinders 40, 41 and 42 of sheet metal, the first two being of polished stainless steel and having an insulating filling 43 therebetween, and the third cylinder being spaced from the second to provide for a draft of cooling air therebetween. The shield 33 is retained in its lowermost position by a pivotally mounted latch 44 on the platform 5.

The poppet valve assembly 18 is actuated by a cam assembly and driving means mounted on a shelf 45 of the table 11 and comprising an electric motor 46 and speed reducer 47 driving a cam shaft 48 which, through a worm 49 and gear 50, drives a second cam shaft 51 which is arranged at right angles to shaft 48. In the embodiment illustrated herein, the shaft 48 is rotated at a speed of 4 R. P. M., and the shaft 51 at a rate of $\frac{1}{6}$ R. P. M., the shaft 51 making one revolution during the processing of each lamp.

The rough vacuum valve 19 is actuated by a cam 52 on shaft 51 through a follower lever 53 which is pivoted on a pin 54 in a bracket 55 on table 11. The lever 53 is connected at one end to the stem of valve 19 and has, at its other end, a roller 56 engaging the cam 52.

The fine vacuum valve 20 and nitrogen gas valve 21 are each actuated by a unique cam arrangement wherein the camming function for each valve is divided between one or a pair of actuating cams on shaft 48 and a shifter cam on the slower speed shaft 51 which serves to connect a follower means with said actuating cam or one or the other of said pair of actuating cams on shaft 48 or to place said follower means in a neutral position where it is out of engagement with either cam. That arrangement provides for a better control of the operations, eliminates cam time for inactive periods in the cycle, and divides the active cam time between the two cams, thereby avoiding the need for a cam of extremely large size.

The nitrogen valve 21 is actuated by a follower lever 57 which is pivoted on a pin 58 and has its upper arm 59 connected to the stem of valve 21. The lower arm 60 of lever 57 has a shiftable end portion 61 pivoted thereto at 62 and carrying rollers 63 and 64 at its lower end. The said end portion 61 of arm 60 is connected by a horizontal spring-loaded connecting rod 65 to an end of a follower arm 66 which is pivoted at its other end on a pin 67 and which carries a roller 68 in engagement with a shifter cam 69 on shaft 51. The said cam 69 thus serves to shift the end portion 61 of lever arm 60, at

predetermined times, to bring the roller 63 into engagement with a cam 70 on shaft 48, or to bring roller 64 into engagement with a cam 71, or to place the arm portion 61 in a neutral position between the actuating cams 70 and 71.

In a similar arrangement, the fine vacuum valve 20 is actuated by a pivotally mounted lever 75 (Fig. 5) which is connected at one end to the stem of valve 20 and at its other end to a link 76 which is connected to a follower arm 77 which is pivoted on a pin 78. The arm 77 has a shiftable lower end portion 79 pivoted thereon at 80 and carrying rollers 81 and 82 which are engageable with respective cams 83 and 84 or movable to a neutral position between those cams by action of a shifter cam 85 which is mounted on shaft 51 and which actuates end portion 79 of arm 77 through a horizontal connecting rod 86 and follower arm 87 which is pivoted at its lower end on the pin 67 and which carries a roller 89 engaging cam 85.

In the operation of the device, the lamp 1 is placed in position on the platform 5 and supporting rollers 9, the rubber sealing ring 15 of the compression chuck 14 is tightened by rotating the arm 17, the contact blocks 22 are engaged with the terminal posts 3 of the lamp by a downward thrust on the lever 27 (although the lamp is not thereby connected to the power supply, this being performed at a later time by a switch actuated by a cam 88 on the shaft 51), and the shield or hood 33 is pulled down around the lamp.

The motor 46 is then connected to a current supply source to start the exhaust and gas filling cycle which is composed of five periods in this case. In the first period, the air is extracted from the lamp, without application of heat, by connecting the lamp to the rough vacuum for a period a little more than one minute. The second period is a flushing cycle during which the lamp is alternately filled with nitrogen to a pressure of 200 mms., for example, and then exhausted to nearly zero pressure by the fine vacuum source. The gas may be admitted and withdrawn about nine times during this period. In the third period, which is another flushing cycle, the filament of the lamp is lighted and the lamp is alternately connected to the nitrogen supply and to the fine vacuum for predetermined times such as to cause the pressure of the gas in the lamp to vary between about 400 mms. and about 200 mms., for example. The admission and withdrawal of the gas may also occur about nine times during this period. In the fourth period, the power supply to the filament is turned off and the lamp is given a final exhaust. In the fifth period, the lamp is brought up to a predetermined final filling pressure of nitrogen, the valves to both the rough and fine vacuum sources being closed. At this time, the lamp is still warm and the gas pressure therein is about 100 mms. above atmospheric. When the lamp has cooled sufficiently to cause the gas pressure to drop below atmospheric, the operator seals it off by fusing the exhaust tube 4 at a point close to the base or neck portion of the bulb between the posts 3.

At the start of the exhaust and gas filling operation, the setting of the cams 52, 85 and 69 and shaft 51 is approximately as shown in Figs. 1 and 5, and all three valves 19, 20 and 21 are closed. The rough vacuum valve 19 is held outwardly in its closed position by lever 53 which has its roller 56 in engagement with an end portion of the extended high surface 90 of cam 52. The fine vacuum valve 20 and the nitrogen valve 21 are held in respective outward and inward closed positions by the respective arm 77 and lever 57 which have their shiftable arm portions 79 and 61 held in neutral positions between respective pairs of cams 83, 84 and 70, 71 by virtue of the fact that the rollers 89 and 68 are in engagement with corresponding surfaces 91 and 92 of intermediate height on the respective cams 85 and 69.

The first period (preliminary exhaust) in the cycle starts when the shaft 51 has rotated clockwise sufficiently

to bring the low surface 93 of cam 90 opposite the roller 56 to permit the lever 53 to be pivoted clockwise and thereby open the rough vacuum valve 19. The lamp 1 is thereby connected through its exhaust tube 4 and passages 94 and 95 (Fig. 3) in the body of the valve assembly 18, with a conduit 96 (Fig. 1) leading to a source of rough vacuum. The lamp is thereby exhausted during rotation of the cam 52 through an angle of about 45°, corresponding to a period of a little more than one minute, before the roller 56 again engages the high surface 90 of cam 52 where it remains for the rest of the entire cycle. During this first period, the intermediate portions 91 and 92 of respective shifter cams 85 and 69 remain in engagement with rollers 89 and 68 to hold the shiftable arms 79 and 61 in their neutral positions so that the fine vacuum valve 20 and the nitrogen valve 21 remain closed.

Shortly thereafter, the second period (a flushing cycle) begins when corresponding low surfaces 97 and 98 of respective shifter cams 85 and 69 come into engagement with rollers 89 and 68, respectively, to cause the arm portions 79 and 61 to be shifted to the left to bring their rollers 81 and 63 into registry with respective actuating cams 83 and 70. This shift occurs at a time when the respective low surfaces 99 and 100 of cams 83 and 70 are opposite the said rollers 81 and 63 which are urged toward said cams by springs 77' and 57' but are held slightly away from actual engagement with said surfaces by the engagement of valves 20 and 21 with their seats. Upon rotation of the cams 83 and 70, the fine vacuum valve 20 and the nitrogen valve 21 are alternately opened by engagement of the high surfaces 101 and 102 of cams 83 and 70 with respective rollers 81 and 63, and closed when the low surfaces 99 and 100 come opposite the said rollers. The valve 20, when opened, connects the exhaust tube 4 of the lamp, through passages 94 and 95, with a conduit 103 leading to a source of fine vacuum. Similarly, the valve 21, when opened, connects the lamp exhaust tube 4, through passages 94 and 95, with a conduit 104 leading to a source of nitrogen of predetermined flow rate. The timing of the valves 20 and 21 by the cams 83 and 70 is so correlated with the flow of the nitrogen supply and the capacity of the fine vacuum source that the lamp is alternately filled with nitrogen to a desired pressure, say about 200 mms., and exhausted to close to zero pressure. In a given case, the timing may be such that the cam 83 holds the vacuum valve 20 open for about 10.5 seconds, and the cam 70 holds the nitrogen valve 21 open for about 4.5 seconds during each revolution. These alternations of flushing and exhausting may occur about nine times over a period of about 2 1/4 minutes.

The third period (another flushing cycle) begins when respective high surfaces 105 and 106 of cams 85 and 69 come into engagement with respective rollers 89 and 68 to cause the shiftable arm portions 79 and 61 to be moved to the right to bring their rollers 82 and 64 into registry with respective cams 84 and 71. This causes the lamp to be again connected alternately with the fine vacuum through valve 20 and with the nitrogen supply through valve 21 by the high surfaces 107 and 108 of respective cams 84 and 71, but for different periods of time than those occurring during the second period described above. Also at the beginning of this third period, power is applied to the filament of the lamp by connecting the terminal blocks 22 to a suitable source of current by means of a switch actuated by the cam 88 on shaft 51. The pressure of nitrogen gas in the lamp may thus be varied between about 400 mms. and 200 mms. during this period by a timing such that the cam 84 holds the fine vacuum valve 20 open for about 9 seconds, and the cam 71 holds the nitrogen valve 21 open for about 6 seconds during each revolution. These alternations occur over a period of about 3 1/4 minutes, after which power to the lamp is turned off by the cam 88.

The fourth period (final exhaust) begins when the cam 98 has rotated to bring a surface 109 of intermediate height into engagement with roller 68 to thereby pull the shiftable arm 61 to a position between the cams 70 and 71 and thereby permit the nitrogen valve 21 to be closed. During this period, the high surface 105 of cam 35 remains in engagement with roller 89 so that the shiftable arm 79 is maintained to the right with its roller 82 in registry with cam 84 to thereby open the fine vacuum valve 20 each time the high surface 107 engages roller 82. This period lasts for approximately 30 seconds, or two revolutions of cam 84.

The fifth period (nitrogen fill) begins when the arm 79 is shifted to the left to a neutral position between cams 83 and 84, to thereby maintain the fine vacuum valve 20 in closed position, by virtue of the fact that the cam 85 has rotated to again bring its surface 91 of intermediate height into engagement with roller 89. At the same time, the cam 69 has brought a low surface 110 into engagement with roller 68 to thereby shift the arm 61 to the left to bring its roller 63 into registry with cam 70 which again causes the nitrogen valve 21 to be opened by the high surface 102 of said cam during two revolutions thereof. During this period, the lamp is filled with nitrogen to a pressure of approximately 860 mms. When the lamp has attained the desired pressure, the nitrogen supply is cut off by an electromagnetic valve 111 (Fig. 1) which is actuated in known manner by a pressure detector (not shown). The cam shafts 48 and 51 continue to be rotated by the motor 46 until power to the motor is shut off by a switch actuated by a cam (not shown) on shaft 51.

When the lamp has cooled so that the gas pressure therein drops below atmospheric, the exhaust tube 4 is fused and sealed off by the operator, the seal between the posts 3 and the glass base end of the bulb 2 being protected from the sealing fires by a suitable shield 112 (Fig. 2).

Instead of deriving the baking heat for the lamp by energizing its filament, the lamp may be heated by a separate external source such as gas flames. In that case it is not necessary to employ two separate flushing cycles (represented by the second and third periods as described above). Further, in that event, it is not necessary to employ a pair of actuating cams 70 and 71 for the nitrogen valve 21, nor a pair of actuating cams 83 and 84 for the fine vacuum valve 20. Rather, it would be necessary to employ but one cam (say cam 70) for the nitrogen valve, and one cam (say cam 83) for the fine vacuum valve, and the respective shifter arms 61 and 79 would then be moved between positions in registry with the respective cams 70 and 83 and neutral positions out of registry with either cam. The resulting single flushing cycle (with variations in nitrogen pressure between about 200 mms. and zero pressure) would be made to extend over a slightly larger period than either of the two separate cycles described above, say a period corresponding to about eleven to fifteen revolutions of shaft 48, by suitable extension of the appropriate surfaces of shifter cams 69 and 85.

It will be understood by those skilled in the art that various changes and modifications in the arrangement and proportions of parts illustrated herein may be made without departing from the spirit and scope of the invention as claimed hereinafter.

What we claim as new and desire to secure by Letters Patent of the United States is:

1. In a device of the character described comprising a fluid flow conduit and valve arranged to control flow of fluid through said conduit, actuating means for said valve comprising a slow speed cam shaft and a high speed cam shaft, means to drive said shafts at predetermined different speeds, an actuating cam on said high speed shaft, follower means connected to said valve and including a shiftable arm portion mounted to be

5 moved into registry with said actuating cam or to a neutral position out of registry with said cam, said actuating cam being configurated to effect movement of said arm portion, when in registry therewith, in directions to cause the follower means to alternately open and close said valve, a shifter cam on said slow speed shaft, and follower means connected to said shiftable arm portion and arranged to be actuated by said shifter cam, said shifter cam being configurated to effect movement of said arm portion alternatively into registry with said actuating cam and to said neutral position for predetermined periods of time.

15 2. In a device of the class described comprising a fluid flow conduit and valve arranged to control flow of fluid through said conduit, actuating means for said valve comprising a slow speed cam shaft and a high speed cam shaft, means to drive said shafts at predetermined different speeds, a pair of actuating cams on said high speed shaft, follower means connected to said valve and 20 including a shiftable arm portion mounted to be moved into registry with either of said actuating cams, said actuating cams each being configurated to effect movement of said arm portion, when in registry therewith, in directions to cause the follower means to alternately open and close said valve, said actuating cams being differently configurated, one from the other, to provide a different timing of the opening and closing of the valve, a shifter cam on said slow speed shaft, and follower means connected to said shiftable arm portion and arranged to be actuated by said shifter cam, said shifter cam being configurated to effect movement of said arm portion alternatively into registry with each of said actuating cams for predetermined periods of time.

35 3. In a device of the class described comprising a fluid flow conduit and valve arranged to control flow of fluid through said conduit, actuating means for said valve comprising a slow speed cam shaft and a high speed cam shaft, means to drive said shafts at predetermined different speeds, a pair of actuating cams on said high speed shaft, follower means connected to said valve and including a shiftable arm portion mounted to be moved into registry with either of said actuating cams and to a neutral position out of registry with either cam, said actuating cams each being configurated to effect movement of said arm portion, when in registry therewith, in directions to cause the follower means to alternately open and close said valve, said actuating cams being differently configurated, one from the other, to provide a different timing of the opening and closing of the valve, a shifter cam on said slow speed shaft, and follower means connected to said shiftable arm portion and arranged to be actuated by said shifter cam, said shifter cam being configurated to effect movement of said arm portion alternatively into registry with each of said actuating cams and to said neutral position for predetermined periods of time.

40 4. In a device of the class described comprising a gas flow conduit and a vacuum conduit and separate valves arranged to control the flow through respective conduits, actuating means for said valves comprising a slow speed cam shaft and a high speed cam shaft, means to drive said shafts at predetermined different speeds, a gas valve actuating cam and a vacuum valve actuating cam on said high speed shaft, follower means associated with each 45 said cam and connected to respective valves and each including a shiftable arm portion mounted to be moved into registry with its associated cam and to a neutral position out of registry with said cam, said actuating cams each being configurated to effect movement of its associated arm portion, when in registry therewith, in directions to cause the respective follower means to alternately open and close its associated valve, a gas shifter cam and a vacuum shifter cam on said slow speed shaft, and follower means associated with each shifter cam and actuated thereby and connected to respective arm portions of

the follower means associated with the respective gas valve actuating cam and vacuum valve actuating cam, each said shifter cam being configurated to effect movement of its associated arm portion alternatively into registry with its associated actuating cam and to a neutral position out of registry with said cam for predetermined periods of time, the gas valve actuating cam and vacuum valve actuating cam having their respective configurations correlated to effect opening of their associated valves at alternative times only.

5. In a device of the class described comprising a gas flow conduit and a vacuum conduit and separate valves arranged to control the flow through respective conduits, actuating means for said valves comprising a slow speed cam shaft and a high speed cam shaft, means to drive said shafts at predetermined different speeds, a pair of gas valve actuating cams and a pair of vacuum valve actuating cams on said high speed shaft, follower means associated with each pair of cams and connected to respective valves and each including a shiftable arm portion mounted to be moved into registry with either of its associated cams and to a neutral position out of registry with either cam, said pairs of cams each being configurated to effect movement of its associated arm portion, when in registry therewith, in directions to cause the respective follower means to alternately open and close its associated valve, the actuating cams of each said pair being differently configurated, one from the other, to provide a different timing of the opening and closing of its associated valve, a gas shifter cam and a vacuum shifter cam on said slow speed shaft, and follower means associated with each shifter cam and actuated thereby and connected to respective arm portions of the follower means associated with the respective pairs of gas valve actuating cams and vacuum valve actuating cams, each said shifter cam being configurated to effect movement of its associated arm portion alternatively into registry with each of the actuating cams of the associated pair and to a neutral position out of registry with either cam of the pair for predetermined periods of time, the pairs of gas valve actuating cams and vacuum valve actuating cams having their respective configurations correlated to effect opening of their associated valves at alternate times only.

6. In combination, a member adapted to be actuated to alternative positions, and means for actuating said member between said positions during a predetermined period comprising a slow speed cam shaft and a high speed cam shaft, means to drive said shafts at predetermined different speeds, an actuating cam on said high speed shaft, follower means connected to said member and including a shiftable arm portion mounted to be moved into registry with said actuating cam or to a neutral position out of registry with said cam, said actuating cam being configurated to effect movement of said arm portion, when in registry therewith, in directions to cause

the follower means to actuate said member between its said alternative positions, a shifter cam on said slow speed shaft, and follower means connected to said shiftable arm portion and arranged to be actuated by said shifter cam, said shifter cam being configurated to effect movement of said arm portion alternatively into registry with said actuating cam and to said neutral position for predetermined periods of time.

7. In combination, a member adapted to be actuated to alternative positions, and means for actuating said member for separate periods of time in cycles differing in timing over each period and comprising a slow speed cam shaft and a high speed cam shaft, means to drive said shafts at predetermined different speeds, a pair of actuating cams on said high speed shaft, follower means connected to said member and including a shiftable arm portion mounted to be moved into registry with either of said actuating cams, said actuating cams each being configurated to effect movement of said arm portion, when in registry therewith, in directions to cause the follower means to actuate said member to its alternative positions, said actuating cams being differently configurated, one from the other, to provide a different timing of the actuation of said member, a shifter cam on said slow speed shaft, and follower means connected to said shiftable arm portion and arranged to be actuated by said shifter cam, said shifter cam being configurated to effect movement of said arm portion alternatively into registry with each of said actuating cams for predetermined periods of time.

8. In combination, a member adapted to be actuated to alternative positions, and means for actuating said member for separate periods of time in cycles differing in timing over each period and comprising a slow speed cam shaft and a high speed cam shaft, means to drive said shafts at predetermined different speeds, a pair of actuating cams on said high speed shaft, follower means connected to said member and including a shiftable arm portion mounted to be moved into registry with either of said actuating cams and to a neutral position out of registry with either cam, said actuating cams each being configurated to effect movement of said arm portion, when in registry therewith, in directions to cause the follower means to actuate said member to its alternative positions, said actuating cams being differently configurated, one from the other, to provide a different timing of the actuation of said member, a shifter cam on said slow speed shaft, and follower means connected to said shiftable arm portion and arranged to be actuated by said shifter cam, said shifter cam being configurated to effect movement of said arm portion alternatively into registry with each of said actuating cams and to said neutral position for predetermined periods of time.
